UNITED STATES PATENT OFFICE.

GEORGE HOLMES COCKS, OF ADRIAN, MICHIGAN.

COMBINATION DRILL-PRESS TABLE AND VISE.

1,341,841.

Specification of Letters Patent. Patented June 1, 1920.

Application filed February 28, 1919. Serial No. 279,815.

To all whom it may concern:

Be it known that I, GEORGE H. COCKS, a citizen of the United States, residing at Adrian, in the county of Lenawee and State 5 of Michigan, have invented certain new and useful Improvements in Combination Drill-Press Tables and Vises, of which the following is a specification, reference being had therein to the accompanying drawings.

10 This invention relates to a combined drill press table and vise, and has for its object the construction of a simple and efficient drill press table that is constituted by a vise structure, and which table can be quickly 15 attached to the arm or bracket of the standard of a drill press.

Another object of the invention is the improvement of the construction of my drill press disclosed in my prior Patent #1,260, 20 513, issued March 26, 1918.

With these and other objects in view, my invention comprises certain novel constructions, combinations, and arrangements of parts as will be hereinafter specifically 25 described, illustrated in the accompanying drawings, and more particularly pointed out in the appended claim.

In the drawings,—

Figure 1 is a view in side elevation of a 30 device constructed in accordance with the present invention, showing the same carried by the arm of a drill press.

Fig. 2 is a top plan view of my combined 35 drill press table and vise, while

Fig. 3 is a longitudinal sectional view of the same.

Fig. 4 is a front view in elevation.

Fig. 5 is a perspective view of the movable 40 jaw of the table and vise.

Referring to the drawings by numerals, 1 designates the column or standard of a 45 drill press, and 2 the arm or bracket slidably mounted upon the standard 1.

My combined table and vise comprises a 50 primary or stationary jaw 3 and an auxiliary or slidable jaw 4. The primary jaw 3 has a broad flat table top 5, corresponding to the broad flat table top 6 of the auxiliary jaw 4, which jaw 3 is provided with an integral, horizontal yoke frame 7, extending outwardly at one side thereof, upon which frame 7 the jaw 4 is mounted, as hereinafter described. Integral with the central portion of the primary or stationary jaw 3 is

a hollow shank 8, and this shank 8 is pivotally mounted in the arm or bracket 2, at 9, so that the combined table and vise can be swiveled or swung upon the bracket 2.

The auxiliary or slidable jaw 4 has a depending extension 10, and through this extension 10 is threaded the bolt 11. The bolt 11 is also extended through the outer end 7^a of the frame 7, and by rotating the outer end of the bolt 11, the slidable jaw 4 can be adjusted longitudinally of the yoke frame 65 7, so as to place it against the stationary jaw 3 or place it away from said jaw to increase the dimensions of the table structure, when it is desired to support a large amount of work upon the combined table and vise. 70 The frame 7 is provided at its sides with outwardly extending flanges 12 that correspond in height to the depending extensions 13 on the auxiliary jaw 4. Secured to the lower face of the extensions 13, by bolts 75 or screws 14, are clamp plates 15, which plates underhang the flanges 12 of the yoke frame, thereby securing the slidable jaw upon the frame 7.

The drill 16 is adapted to pass between 80 the jaws 3 and 4 when the jaws are separated, as shown in Fig. 1, thereby obviating the necessity of cutting a hole in the table, as would be the case if it were made solid as in my prior Patent #1,260,513, and if a 85 large piece of work is desired to be supported upon the table, the slidable jaw 4 can be moved to the extreme outer end of the frame 7, thereby producing a very efficient table, but when it is desired to clamp a 90 piece of work upon the table, it is not necessary to bring extra devices or implements into play, but all that the operator has to do is to close this sliding jaw 4 upon the object or piece of work, causing the object 95 or work to be gripped between the supporting edges 3^a and 4^a of the stationary and sliding jaws, respectively.

The jaws are provided with suitable slots 17 for lightening the weight of said jaws, 100 and further for permitting the trash or shavings or the like to drop therethrough and readily clear the upper face of the jaws constituting the table.

I wish it to be understood that I reserve 105 the right to make such alterations or modifications in the manufacture of my device as shall appear to one skilled in the art to

which this invention relates, which alterations or modifications shall fairly fall within the scope of the appended claim.

What I claim is:

- 5 In a device of the class described, the combination with a support, of a stationary jaw carried by said support and provided with a flat outwardly-extending table-like top portion, a slideable jaw supported contiguous

to said stationary jaw and provided with a flat outwardly-extending table-like top portion, and said jaws when closed forming a flat top table, substantially as shown and described.

In testimony whereof I hereunto affix my signature.

GEORGE HOLMES COCKS.
